UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

1,257,720.

Specification of Letters Patent. Patented Feb. 26, 1918.

Application filed July 2, 1917. Serial No. 178,242.

To all whom it may concern:

Be it known that I, ALBEN E. LUNDELL, a citizen of the United States, residing at New York, in the county of Bronx and State 5 of New York, have invented certain new and useful Improvements in Automatic Telephone-Exchange Systems, of which the following is a full, clear, concise, and exact description.

10 This invention relates to automatic telephone exchange systems, and particularly to impulse controlling systems for automatic telephone exchanges.

It is the object of the present invention to 15 provide a new and useful circuit arrangement for controlling the operation of apparatus employed for determining the setting of selectively operable switching devices.

20 In automatic telephone exchanges in which an impulse sending or controlling apparatus is adjusted in accordance with the various digits of the desired line number for controlling the establishment of a connection by setting a plurality of selectively operable 25 switching devices, the sending apparatus cannot be used for controlling the establishment of another connection until it has successfully completed the control of the first connection. The sending apparatus is set by 30 the subscriber or operator in accordance with all the digits of the called number. If, for any reason, for instance, a selector finds all the available trunk outlets busy, the sending apparatus is prevented from sending or 35 receiving the impulses representing all the digits of the called number, it will remain set for controlling the sending of a certain number of impulses, and thus be unavailable for use in the control of the establishment 40 of other connections until the operator or subscriber restores it to normal. In order to insure in such cases the prompt restoration of the sending device, in accordance with one feature of the present invention, the sender 45 may be automatically run down (restored to normal) at certain stages of its operation and independently of the control of the selector switches. If one of the selector switches finds all the trunks of a desired group busy, 50 then it connects the sender to an overflow switching arrangement under the control of which the sender is restored to normal in the same manner as under the control of the other selector switches, the setting of which 55 could not be effected.

In accordance with another feature of the invention means are provided for sending the proper signals to the operators supervising the connection if a selector switch seizes an overflow trunk. 60

The drawings, when placed together as indicated in Figure 6, represent a semi-mechanical telephone exchange system embodying the various features of the present invention. 65

The selector switches employed in the present system are preferably of the type disclosed in a patent to E. B. Craft and J. N. Reynolds, No. 1,123,696, and the sequence switches are of the structure shown in Patent No. 1,127,808. The sending device is of substantially the same type as the one disclosed in a patent to A. E. Lundell, No. 1,169,819, but in its stead other well-known sending devices, especially those employed 70 in semi-mechanical telephone exchange systems, may be used. 75

Only so much is shown of the circuits and controlling apparatus as is necessary for a clear understanding of the invention. 80

The subscriber at station 100 desiring to obtain a connection with a subscriber at station 300, removes his receiver from the switchhook, closing thus an energizing circuit for his line relay 101. The line relay 85 by attracting its armature causes the lighting of a line lamp 102, whereupon an A operator inserts an answering plug 103 in which one end of her cord circuit 104 terminates, into the answering jack 105 of the 90 calling line. A circuit is closed thereupon from grounded battery, through a calling supervisory lamp 106, a resistance 107, the sleeve contacts of plug 103 and jack 105, the winding of a cut-off relay 108, to ground. 95 The cut-off relay becomes energized and opens the circuit of the line relay 101, whereupon the lamp 102 is extinguished. The lamp 106 will not be lighted, because a shunt is closed around it through the 100 armature and front contact of an answering supervisory relay 109 that was energized in the well-known manner through the calling subscriber's line circuit. After the A operator learned from the calling subscriber 105 the number of the desired subscriber's line, she communicates with a B operator through a call circuit (not shown). The B operator controls the completion of the connection at the exchange at which the called subscriber's 110

line terminates. The B operator instructs the A operator to extend the calling line to an idle trunk 110, 111 and depresses her assignment key 120 for causing the association of an idle sender with a selector 121 by means of which the trunk 110, 111 may be extended. A circuit is closed from ground through the contact of key 120, the upper contact of a sequence switch spring 122, and the power magnet of a sequence switch 123, to grounded battery, whereupon the sequence switch is moved out of position 1 and under the control of its master contact 124 into position 2. While the sequence switch 123 is in positions 2 to 18 the sequence switch contact 163 is closed and the lamp 165 lighted. The lighting of lamp 165 indicates to the B operator the busy condition of trunk 110, 111. A circuit is closed from ground through upper right-hand contact of a sequence switch spring 125, a conductor 126, the upper right-hand contact of a sequence switch spring 500, and the power magnet of a sequence switch 501 to grounded battery. The sequence switch 501 is moved out of position 1 and under the control of its master contact 502 into position 2. A circuit is then closed from grounded battery, through the winding of a magnet 503, a sequence switch contact 504, and the left-hand back contact and armature of a relay 505 to ground. The magnet becomes energized and causes the upward movement of a cord finder switch. As soon as the wipers of the cord finder reach a set of terminals individual to the trunk 110, 111, a circuit is closed from ground through the lower left-hand contact of sequence switch spring 125, a conductor 127, cord finder wiper 506, the lower contact of a sequence switch spring 507, and the winding of relay 505, to grounded battery. The relay 505 becomes energized and closes a locking circuit for itself through the upper contact of a sequence switch spring 507, the outer left-hand front contact and armature of relay 505, a cord finder wiper 508, a conductor 509, and the lower right-hand contact of sequence switch spring 125, to ground, the relay 505 becomes energized and opens at its left-hand back contact the circuit of magnet 503, whereupon the cord finder is arrested in its upward travel. At its inner left-hand front contact and armature, the relay 505 closes a circuit through the lower right-hand contact of sequence switch spring 500, for driving the sequence switch 502 out of position 2 and into position 3.

60 The B operator adjusts the sender (Fig. 4) in accordance with the number of the called line by depressing keys 510, 511, 512 and 542, representing the thousands, hundreds, tens and units digits, respectively, of the desired number. She then depresses a

start key 513 and thus closes a circuit from ground through the contact of this start key, the upper contact of a sequence switch spring 514, and the power magnet of sequence switch 501, to grounded battery, for 70 moving this sequence switch out of position 3 and into position 4. A fundamental circuit is now closed from ground through the lower contact of a sequence switch spring 128, a conductor 129, a cord finder wiper 517, 75 the outer left-hand armature and back contact of an upper zero counting relay 518, a sequence switch contact 519, the windings of a stepping relay 520, a cord finder wiper 521, a conductor 522, the lower left-hand contact of a sequence switch spring 130, and the winding of a relay 131 to grounded battery. The relays 131 and 520 become energized. Relay 520 closes a circuit from ground through its armature and front contact, the upper left hand contact of a sequence switch spring 516, the contact of key 510, and the winding of a lower zero counting relay 515, to grounded battery. The relay 515 becomes energized and closes a locking 80 circuit for itself from ground, through a sequence switch contact 525, the armature and front contact of relay 515, and the windings of counting relays 518 and 515, to grounded battery. The counting relay 518 85 cannot become energized, because its winding is shunted through a grounded path closed at the front contact of the stepping relay 520.

The relay 131 closes a locking circuit for 100 itself through its right-hand armature and the upper contacts of sequence switch spring 130, and also closes a circuit from ground through its left-hand armature and front contact, the upper right-hand contact of a 105 sequence switch spring 132, and the power magnet of sequence switch 123 to grounded battery, for moving this sequence switch out of position 2 and into position 3. A circuit is then closed from ground through the left-hand armature and front contact of relay 131, the lower left-hand and the upper right-hand contacts of a sequence switch spring 133, and the winding of a magnet 134 to 110 grounded battery. The magnet 134 becomes energized and causes wipers 135, 136 and 137, and a commutator brush 138 of selector 121, to move in an upward direction. When the commutator brush 138 engages a conducting segment 139, it connects ground 115 through conductor 140', and the lower right-hand and upper left-hand contacts of sequence switch spring 130, to the winding of relay 131, whereupon the stepping relay 520 is shunted out, and by releasing its 120 armature, permits the energization of the upper counting relay 518. The counting relay 518 opens at its left-hand back contact the fundamental circuit and closes a circuit 125 from ground through its left-hand armature 130

and front contact the lower contact of sequence switch spring 514, and the power magnet of sequence switch 501, to grounded battery, for moving this sequence switch out 5 of position 4 and into position 6. When the sequence switch 501 moves out of position 4, the relays 515 and 518 become deenergized. Due to the opening of the fundamental circuit, the relay 520 becomes de- 10 energized, but the relay 131 remains energized as long as the brush 138 is in engagement with segment 139. As soon, however, as the brush 138 leaves the segment 139, the relay 131 becomes deenergized and closes 15 a circuit from ground through its left-hand armature and back contact, the lower right-hand contact of sequence switch spring 132, and the power magnet of sequence switch 123, to grounded battery, for moving this 20 sequence switch out of position 3 and into position 7. When the sequence switch 123 reaches position 7, a circuit is closed from ground through the lower contact of a sequence switch spring 140, and the left- 25 hand winding of a test relay 141 to grounded battery. The relay 141 becomes energized and closes a circuit from ground through its left-hand armature and front contact, the upper contact of a sequence 30 switch spring 142, and the power magnet of sequence switch 123, to grounded battery, for moving this sequence switch out of position 7 and into position 8. As soon as the sequence switch leaves position 7, the lower 35 contact of sequence switch spring 140 is opened, and assuming that the first trunk in the desired group is idle, the relay 141 will not find a locking circuit for its right-hand winding and becomes deenergized. A 40 circuit is then closed from ground through the left-hand armature and back contact of relay 141, the lower contact of sequence switch spring 142, and the power magnet of sequence switch 123 to grounded battery, for 45 moving this sequence switch out of position 8 and into position 10. Another circuit is closed from ground through the lower left-hand and upper contacts of a sequence switch spring 143, wiper 137, a test terminal 50 144 and multiples thereof, a conductor 200, and the winding of a relay 201, to grounded battery. Relay 201 becomes energized and due to the connection of ground through the lower right-hand contact of sequence switch 55 143 and the wiper 137 to the multiples of test terminal 144, this terminal is guarded against seizure by other selectors in a manner to be hereinafter set forth.

Upon the successful setting of selector 121 60 in accordance with the thousands digit, a fundamental circuit is closed from ground through the upper contact of a sequence switch spring 202, a conductor 203, selector wiper 135, a sequence switch contact 145, 65 conductor 522, cord finder wiper 521, the windings of stepping relay 520, sequence switch contact 519, the outer left-hand back contact and armature of relay 518, cord finder wiper 517, conductor 129, the upper contact of sequence switch spring 128, selector wiper 136, a conductor 204, the lower right-hand contact of a sequence switch spring 205, and the winding of a relay 206, to grounded battery. The relay 206 becomes energized and locks up through its left- 70 hand armature and the lower left-hand contact of sequence switch spring 205. The relay 520 closes a circuit from ground through its armature and front contact, the upper right-hand contact of sequence switch 80 spring 516, the contact of key 511, the armature and back contact of a counting relay 530, and the winding of a counting relay 531, to grounded battery. The relay 531 closes a locking circuit from ground 85 through sequence switch contact 525, the left-hand armature and front contact of relay 531, and the windings of relays 530 and 531, to grounded battery. Due to the shunt closed around the winding of relay 90 530 through the front contact of relay 520, the former relay cannot become energized. The relay 206 closes a circuit from ground through its right-hand armature and front contact, the upper right-hand contact of a 95 sequence switch spring 206', and the power magnet of sequence switch 207, to grounded battery. The sequence switch is moved out of position 1 and under the control of its master contact 208, into position 2. In this 100 position of the sequence switch 207, a circuit is closed from grounded battery, through the winding of a magnet 209, a sequence switch contact 210', and the right-hand front contact and armature of relay 105 206, to ground. The magnet 209 becomes energized and causes the movement of wipers 210, 211 and 212, and commutator brush 213 of a selector 214, in an upward direction. As soon as the brush 213 engages a conducting plate 215, it connects ground through conductor 216, and a sequence switch contact 217 to the winding of relay 206, causing thus the shunting out of the stepping relay 520, whereupon the count- 110 ing relay 530 becomes energized and locks up. As soon as the commutator brush 213 leaves the conducting plate 215, the relay 520 becomes again energized and connects ground through key 511 and the armature 115 and front contact of relay 530, to the winding of relay 515. This relay becomes energized and operates in the above described manner to prepare the energizing circuit of relay 518. As soon as the commutator 120 brush 213 again engages the conducting plate 215, the relay 518 becomes energized and opens the fundamental circuit. The relay 206 is maintained energized until the commutator brush 213 leaves the conducting 125 130

- plate 215. Due to the energization of relay 518, the above traced circuit for sequence switch 500 is again closed, and this sequence switch is driven out of position 6 and into position 8, whereupon the counting relays are unlocked. Upon the deenergization of relay 206 a circuit is established from ground, through the right-hand armature and back contact of this relay, the upper 5 left-hand contact of sequence switch spring 206', and the power magnet of sequence switch 207, to grounded battery for driving this sequence switch out of position 2 and into position 16. The magnet 209 becomes deenergized and assuming that the first 10 trunk in the desired group is idle, the selector 214 is arrested with its wipers 212, 211 and 210, on the terminals of trunks 221, 222 and 306.
- 15 20 Upon the setting of selector 214 in accordance with the hundreds digit of the desired number, a circuit is closed from ground, through a sequence switch contact 220, test wiper 212, conductor 221, and the 25 winding of a relay 300 to grounded battery. The relay 300 becomes energized. A fundamental circuit is closed from ground, the lower contact of a sequence switch spring 305, conductor 306, wiper 210, the lower contact 30 of sequence switch spring 202, conductor 203, selector wiper 135, sequence switch contact 145, conductor 522, cord finder wiper 521, the windings of relay 520, sequence switch contact 519, outer left-hand back contact and armature of relay 518, cord finder wiper 517, conductor 129, the upper contact 35 of sequence switch spring 128, selector wiper 136, conductor 204, the upper contact of sequence switch spring 205, selector wiper 211, conductor 222, the lower right-hand contact 40 of a sequence switch spring 307, and the winding of a relay 308, to grounded battery. The relay 308 becomes energized. Relay 308 closes a locking circuit for itself 45 through its left-hand front contact and armature, and the lower left-hand contact of sequence switch spring 307, and a driving circuit for sequence switch 310 from ground through its right-hand armature and front contact, the upper right-hand contact 50 of a sequence switch spring 309, and the power magnet of a sequence switch 310, to grounded battery. The sequence switch 310 is moved out of position 1, and under the 55 control of its master contact 311, into position 2. A circuit is closed thereupon from grounded battery, through the winding of a magnet 312, a sequence switch contact 313, and the right-hand front contact and armature 60 of relay 308, to ground. The magnet 312 causes connector 314 with its wipers 315, 316 and 317 and commutator brushes 318 and 319, to move in an upward direction. The relay 520 closes a circuit from ground 65 through its armature and front contact, the lower right-hand contacts of sequence switch spring 516, a contact of key 512, the armature and back contact of counting relay 540, and the winding of counting relay 541, to grounded battery. The relay 541 becomes 70 energized and locks up through the winding of relay 540, the latter being prevented from energizing as long as the stepping relay 520 keeps its armature attracted. As soon as the commutator brush 318 engages a conducting 75 plate 320, a ground is connected through brush 318, plate 320, the lower contact of a sequence switch spring 321, and the left-hand armature and front contact of relay 308, to the winding of this relay. The stepping relay 520 becomes deenergized thereupon, and permits the energization of relay 540, whereupon relay 540 locks up and causes the energization of relay 531 in the above 80 explained manner. Relay 531 becomes energized and prepares a locking circuit for itself through the winding of relay 530. In view of the fact, however, that in the meantime the commutator brush 318 has left the conducting segment 320 and the stepping relay 520 became energized, the relay 530 cannot become energized. When the commutator brush 318 reengages the conducting plate 320, the relay 520, by releasing its armature, permits the energization of relay 530 85 and the latter causes the energization of relay 515. Relay 515 locks up and prepares the energizing circuit of relay 518, and as soon as the commutator brush 318 engages for the third time the conducting segment 90 320, the relay 518 becomes energized, opens the fundamental circuit and causes the movement of sequence switch 501 out of position 8 and into position 10. Upon the opening 95 of the fundamental circuit, relay 308 becomes deenergized. The setting of the connector in accordance with the tens digit of the called number is now completed. In response to the deenergization of relay 308, the magnet 312 becomes deenergized and the 100 connector 314 is arrested in its upward travel. Relay 308 closes a circuit from ground through its right-hand armature and back contact, the upper left-hand contact of sequence switch spring 309, and the power 105 magnet of sequence switch 310, to grounded battery, whereupon the sequence switch is driven out of position 2 and into position 3. Upon the reclosure of the fundamental circuit, the relay 308 becomes again energized. The relay 308 locks up in the above described 110 manner and closes a circuit from ground through its right-hand armature and front contact, the upper right-hand contact of sequence switch spring 309, and the power 115 magnet of sequence switch 310, for driving this sequence switch out of position 3 and into position 4. The circuit of the driving magnet 312 is now again closed and the connector caused to further travel in an up- 120 125 130

ward direction. Upon energization, the stepping relay 520 closes a circuit for the counting relay 541 in the same manner as described in connection with the tens selection, the circuit leading through sequence switch contact 516 and the contact of key 542. The step-by-step actuation of the counting relays is accomplished now, the energization and deenergization of the stepping relay 520 being controlled by the commutator brush 319 engaging and disengaging a commutator plate 322. Upon the energization of the upper zero counting relay 518, the units selection is completed and the fundamental circuit is opened. The relays 520 and 308 become deenergized. The relay 518 causes the movement of sequence switch 501 out of position 10 and into position 16, whereupon the counting relays are unlocked. The relay 308 closes through its right-hand back contact a circuit for moving the sequence switch 310 out of position 4 and into position 16. While the sequence switch 310 is moving from position 4 to 16, the ringing of the called party is accomplished in the well-known manner, the ringing circuit being closed in position 12 of the sequence switch from a ringing current source 323, through the lower contacts of sequence switch springs 324 and 325.

While the sequence switch 501 is moving from position 11 to position 13 the circuit of magnets 570 is closed and these magnets cause the restoration to normal of the depressed keys 510, 511, 512, 513 and 542. When the sequence switch 501 reaches position 16, a circuit is closed from ground through the lower contact, sequence switch spring 550, cord finder wiper 551, conductor 552, the lower left-hand contact of sequence switch spring 132, and the power magnet of sequence switch 123 to grounded battery. The sequence switch 123 is moved out of position 10 and into position 16. As soon as the sequence switch 123 leaves position 10 and opens the lower right-hand contact of sequence switch spring 125, the locking circuit of relay 505 is opened and this relay by deenergizing closes a circuit from ground through its inner left-hand armature and back contact, the lower left-hand contact of sequence switch spring 500, and the power magnet of sequence switch 501, to grounded battery, for moving this sequence switch out of position 16 and into position 17. A circuit is then closed from ground through a sequence switch contact 553, and the winding of a magnet 554, to grounded battery. The magnet 554 becomes energized and causes the downward movement of the cord finder. As soon as the cord finder reaches its normal position and a commutator brush 555 carried by the cord finder engages a conducting plate 556, a ground is connected through the upper left-hand con-

tact of sequence switch spring 500, and the power magnet of sequence switch 501, to grounded battery, for moving this sequence switch out of position 17 and into position 1.

In the meantime the A operator has inserted a plug 112 into a jack 113 in which the assigned trunk 110, 111 terminates. A circuit is then closed from grounded battery, through a calling supervisory lamp 114, a resistance 115, the sleeve contacts of plug 112 and jack 113, the left-hand winding of a relay 150 and the armature and back contact of a polarized relay 151, to ground. The relay 150 becomes energized and the lamp 114 lights up. The relay 151 operates only when the positive (grounded) pole of battery is connected to its lower terminal and the negative pole to its upper terminal. For this reason, if the A operator inserts the plug 112 into the jack 113 while the sequence switch 123 is standing in some position between 1 and 14; that is to say, prior to the complete setting up of the connection, a circuit is closed from the (negative) pole of battery, through the upper contact of a sequence switch spring 152, the lower winding of a relay 153, trunk conductor 111, the armature and front contact of relay 150, the winding of relay 151, trunk conductor 110, the upper winding of relay 153, and the lower contact of a sequence switch spring 155, to the (positive) pole of battery. Relay 151 does not become energized, but relay 153 becomes energized. When the connection is cut through, i. e., when sequence switches 123, 207 and 310 reach position 16, a circuit is closed from the (positive) pole of battery, through the left-hand winding of relay 301, contact 302 of relay 303, the primary winding of repeating coil 304, the upper contact of sequence switch spring 305, conductor 306, selector wiper 210, the lower contact of sequence switch spring 202, conductor 203, selector wiper 135, the upper contact of sequence switch spring 155, the winding of relay 153, the winding of relay 151, the front contact and armature of relay 150, the lower winding of relay 153, the lower contact of sequence switch spring 152, selector wiper 136, conductor 204, the upper contact of sequence switch spring 205, selector wiper 211, conductor 222, the upper contact of sequence switch spring 307, the primary winding of repeating coil 304, contact 330 of relay 303, and the right-hand winding of relay 301, to the negative pole of battery. Relay 301 becomes energized, but relay 151 remains deenergized. As soon as the called subscriber removes his receiver from the switchhook, a supervisory relay 332 becomes energized in the well-known manner. The relay 332 closes a circuit from ground through the armature and front contact of relay 301, the front contact 130

and armature of relay 332, and the winding of relay 303, to grounded battery. Relay 303 becomes energized, opens in its back contacts the above traced circuit of relays 301 5 and 151, and closes a new circuit for these relays through its front contacts. In this new circuit the connection to battery is reversed and the relay 151 becomes energized. By opening its back contact, the relay 151 10 disconnects the lamp 114 from the low resistance path that was closed through the left-hand winding of relay 150 and causes thus the extinguishment of lamp 114.

When disconnection is desired the sub- 15 scribes restore their receivers to the switch-hooks. Upon the restoration of the receiver at the called station 300, the relay 332 becomes deenergized and causes in turn the deenergization of relay 303. The relay 303 re- 20 closes at its contacts 302 and 330, the originally traced energizing circuit including the relays 301 and 151, whereupon the relay 151 becomes deenergized and permits the lamp 114 to light up. Upon the restoration of the 25 receiver at the calling station 100, the relay 109 becomes deenergized and opens the shunt around the lamp 106, whereupon this lamp lights up. The A operator, noticing the lamps 106 and 114 lighted, removes 30 plugs 103 and 112 from jacks 105 and 113, respectively. Relays 108 and 150 become deenergized and lamps 106 and 114 become extinguished. Upon the deenergization of 35 relay 150, relay 153 becomes deenergized and closes a circuit from ground through its armature and back contact, a sequence switch contact 160, and a disconnect lamp 161, to grounded battery. The lamp 161 lights up, whereupon the B operator depresses her dis- 40 connect key 162. A circuit is now closed from ground through sequence switch contact 163, the contact of key 162, and the winding of a relay 164, to grounded battery. The relay 164 locks up through its left- 45 hand front contact and armature and closes a circuit from ground through its right-hand armature and front contact, the lower contact of sequence switch spring 192, and the power magnet of sequence switch 123, to grounded battery, for driving this se- 50 quence switch out of position 16 and into position 18. A circuit is now closed from grounded battery, through the winding of a magnet 166, and a sequence switch contact 55 167, to ground. The magnet 166 becomes energized and causes the downward travel of the selector switch 121. When the selector 121 reaches its normal position and the commutator brush 138 engages a normal 60 segment 168, a ground is connected through the upper left-hand contact of sequence switch spring 132, and the power magnet of sequence switch 123, to grounded battery, for driving this sequence switch out of posi- 65 tion 18 and into position 1. Magnet 166 and

relay 164 become deenergized, and the lamps 161 and 165 become extinguished.

As soon as the test wiper 137 disengages the terminal 144, the relay 201 becomes deenergized and closes a circuit from ground 70 through its armature and back contact, the lower left-hand contact of sequence switch spring 206', and the power magnet of sequence switch 207 to grounded battery, for driving this sequence switch out of position 75 16 and into position 18. A circuit is now closed from ground through a sequence switch contact 240, and the winding of a magnet 241, to grounded battery. The magnet 241 becomes energized and causes the restoration of selector 214. When the selector 214 reaches its normal position, and the commutator brush 213 engages a normal conducting segment 242, a ground is connected through the lower right-hand contact 80 of sequence switch spring 206', and the power magnet of sequence switch 207, to grounded battery, whereupon the sequence switch 207 is driven out of position 18 and into position 1, whereupon the magnet 241 90 becomes deenergized.

As soon as the wiper 212 of selector 214 leaves the terminal of test conductor 221, the relay 300 becomes deenergized and closes a circuit from ground, through its armature 95 and back contact, the lower left-hand contact of sequence switch spring 309, and the power magnet of sequence switch 310, to grounded battery, for moving this sequence switch out of position 16 and into position 100 18. A circuit is now closed from ground through a sequence switch contact 340 and the winding of a magnet 341, to grounded battery. Magnet 341 becomes energized and causes the downward travel of the connector 314. When the connector reaches its normal position, a circuit is closed from ground through commutator brush 318, a normal conducting segment 342, the lower right-hand contact of sequence switch spring 105 309, and the power magnet of sequence switch 310, to grounded battery. The sequence switch moves into position 1. The magnet 341 and the relay 301 become de- 110 energized.

As above stated, the busy condition of trunks terminating in stationary contacts of selector 121 is indicated by a ground connected through the lower right-hand contact and upper contact of a sequence switch 120 spring 143, and a test wiper 137 to test terminals 144 and multiples thereof. For this reason, after the sending of the thousands impulses from selector 121 to the sender; that is to say, after the completion of the 125 group selecting operation of the selector 121, a locking circuit is established for the test relay 141 from grounded battery, through the right-hand winding, front contact and armature of this relay, lower left-hand con- 130

tact and the upper right-hand contact of sequence switch spring 143, selector wiper 137, test terminal 144, and thence through the test wiper 137 of another selector and the 5 lower right-hand contact of spring 143 of another sequence switch 123 to ground. Due to the fact that in position 8 of the sequence switch 123 the relay 141 is energized, the sequence switch 123 will not be moved out of 10 position 8 and for this reason a circuit is closed from ground, through the left-hand armature and front contact of relay 141, the upper contacts of sequence switch spring 133 and the winding of magnet 134 to 15 grounded battery. Under the control of magnet 134 the selector 121 is caused to continue its upward travel. As long as the test wiper 137 engages test terminals that are thus grounded through test wipers of other 20 selector switches, the relay 141 remains locked up and maintains the circuit of magnet 134 closed. As soon as an idle test terminal is engaged by the test wiper, the locking circuit of relay 141 is opened and this 25 relay opens at its left-hand front contact the driving circuit of magnet 134, and closes at its left-hand back contact a circuit for driving the sequence switch 123 out of position 8 and into position 10, whereupon the establishment of the connection is completed in 30 the above described manner.

If, however, all the trunks in the selected group are busy, then the selector 121 is caused to move with its wipers into engagement with terminals of an overflow trunk 35 400, 401, 402 (Fig. 4). The relay 141 becomes deenergized thereupon and causes in the above described manner the arresting of the selector 121 and the movement of 40 sequence switch 123 out of position 8 and into position 10. A circuit is now closed from ground through the winding of marginal relay 403, the lower winding of a relay 404, the lower contact of a sequence 45 switch spring 405, conductor 400, wiper 135, sequence switch contact 145, conductor 522, cord finder wiper 521, the winding of stepping relay 520, sequence switch contact 519, the outer left-hand back contact and armature of counting relay 518, cord finder 50 wiper 517, conductor 129, the upper contact of sequence switch spring 128, selector wiper 136, conductor 401, the lower contact of a sequence switch spring 406, and the upper 55 winding of relay 404 to grounded battery. The relays 403, 404 and 520 become energized. The relay 520 closes the above traced circuit through the contact of key 511 and the winding of counting relay 531, whereupon 60 the latter becomes energized, closes a locking circuit for itself and prepares the circuit for the upper counting relay 530. The counting relay 530 is prevented from energizing as long as the stepping relay 520 65 is energized. The relay 404 closes a circuit

from ground through its armature and front contact, a sequence switch contact 407, and the power magnet of a sequence switch 408, to grounded battery. The sequence switch 408 is moved out of position 1 and under 70 the control of its normal contact 409, is moved toward position 18.

When the sequence switch 408 reaches position 1-3/4 the marginal relay 403 locks up through a circuit traceable from ground 75 through the winding of relay 403, the lower contact of a sequence switch spring 430, front contact and armature of relay 403, and the winding of a relay 422 to grounded battery. The relay 422 becomes energized 80 and by opening its back contacts prevents the closure of circuit paths in which current flows in a direction opposite to that normally used for causing the energization of the stepping relay 520. But for this relay 85 422, the adjustment of relay 520 might be destroyed by a reversal in the direction of the current-flow.

When the sequence switch 408 reaches position 2, a circuit is closed from grounded 90 battery, through the winding of a magnet 420, sequence switch contact 421, conductor 402, selector wiper 137, and the upper right-hand and lower right-hand contacts of sequence switch spring 143, to ground. The 95 magnet 420 becomes energized, locks up through its front contact, and operates a well-known message register for indicating the number of the overflow calls in the respective group.

When the sequence switch 408 leaves position 2, and until it reaches position 3, the above-traced circuit for relays 520 and 404 is opened in the lower left-hand contact of sequence switch spring 406. The deenergization of relay 404 does not affect the operation of sequence switch 408. Upon the deenergization of relay 520 the counting relay 530 is permitted to become energized, and as soon as the sequence switch 408 100 reaches position 3 and recloses the circuit at the lower left-hand contact of sequence switch spring 406, the relay 520 again becomes energized and causes the closure of a circuit through the front contact of relay 105 530 for energizing relay 515. The relay 518 will be energized by current flowing through a circuit prepared by relay 515 as soon as the sequence switch 408 moves out of position 3 and causes the deenergization of stepping relay 520 by reopening the circuit in the lower left-hand contact of sequence switch spring 406. The relay 518 operates in the same manner as described in the establishment of the telephonic connection.

As soon as the sequence switch 501 reaches position 8 and the sequence switch 408 recloses the above-traced controlling or fundamental circuit at the lower left-hand contact of sequence switch spring 406, the relays 404 110

and 520 become deenergized. Assuming that this happens when the sequence switch 408 is in position 7, it will be seen that the stepping relay 520 causes the operation of the 5 counting relay 540, while the sequence switch 408 is moving from position 7 to position 8; the operation of counting relay 530 while the sequence switch 408 is moving from position 8 to position 9; and the operation of 10 the counting relay 518 while the sequence switch 408 is moving from position 9 to position 12. Upon the actuation of the counting relay 518 the sequence switch 501 is moved out of position 8 and into position 15 10, and the counting relays are unlocked.

While the sequence switch 408 is moving from position 9 to position 18-1/2, the lower left-hand contact of sequence switch spring 406 is opened, but as soon as the sequence 20 switch reaches position 12 and until it moves out of position 17 a sequence switch contact 431 is closed, whereupon the fundamental circuit is again established, but extends now from grounded battery, through the upper 25 winding of relay 404, the right-hand armature and front contact of relay 422, sequence switch contact 431, conductor 401, and then through the above-traced path and back through conductor 400, the upper right-hand 30 contact of sequence switch spring 405, the left-hand front contact and armature of relay 422, the lower winding of relay 404 and the winding of relay 403 to ground. The stepping relay 520 becomes energized, and 35 causes through the agency of key 542 the energization of counting relay 541. Upon the opening of this circuit at sequence switch contact 431, the relay 520 becomes energized and permits the energization of 40 counting relay 540.

When the sequence switch 408 reaches position 18-1/2 the fundamental circuit traced through the lower right-hand contact of sequence switch spring 405 and lower left-hand contact of sequence switch spring 406 is again closed. The relay 520 becomes energized and causes in turn the energization of counting relay 531. Relay 404 being energized, when the sequence switch 408 reaches 45 position 1, it will be caused to perform another revolution. When it leaves position 2, the fundamental circuit is opened at the lower left-hand contact of sequence switch spring 406. The stepping relay 520 becomes 50 deenergized and permits the energization of counting relay 530. When the sequence switch 408 reaches position 3 the relay 520 is again energized and causes the energization of counting relay 515, and when the sequence switch 408 reaches 55 position 4, it will be caused to perform another revolution. When it leaves position 5, the relay 520 becomes deenergized and causes in turn the energization of the counting relay 518. The counting relay 518 opens the fundamental circuit and causes the 60 sequence switch 408 moves out of position 3, the relay 520 becomes deenergized and causes in turn the energization of the counting relay 518. The counting relay 518 opens the fundamental circuit and causes the 65 movement of sequence switch 501 into posi-

tion 16, whereupon the sequence switch 123 is moved into position 16 and the cord finder is released in the above described manner.

As soon as the sequence switch 408 moves out of position 14 and opens its contact 430, 70 the locking circuit including relays 403 and 422 is opened and these relays become deenergized. As soon as the sequence switch 123 reaches position 14-3/4 and while sequence switch 408 is in positions 1-3/4 to 75 18-3/4, a circuit is closed from ground through the primary winding of an induction coil 418, a condenser 419, the upper left-hand contact of sequence switch spring 405, conductor 400, selector wiper 135, sequence switch contact 155, trunk conductor 110, the tip contacts of jack 113 and plug 112, and the secondary winding of a repeating coil 154 to ground. A tone is induced into this circuit by a device 417 that is connected in 80 circuit through a sequence switch contact 415, and thus the A operator receives an audible signal indicating that the selector 121 seized the overflow trunk.

Another circuit is closed from the negative pole of grounded battery, through the upper winding of relay 404, the right-hand armature and back contact of relay 422, the upper right-hand contact of sequence switch spring 405, conductor 400, selector wiper 135, 90 upper contact of sequence switch spring 155, the upper winding of relay 153, the winding of the polarized relay 151, the front contact and armature of relay 150, the lower winding of relay 153, lower contact of sequence switch spring 152, selector wiper 126, conductor 401, the upper right-hand contact of sequence switch spring 406, the left-hand back contact and armature of relay 422, the lower winding of relay 404, and the winding 95 of the marginal relay 403 to the positive pole of battery. Relays 404 and 153 become energized, but due to the relatively high resistance of the windings of relay 153, the marginal relay 403 cannot pull up its armature, 100 and leaves the relay 422 deenergized. The current flowing in this circuit is of the proper direction to cause the energization of relay 151 which, in the above-described manner, causes the extinguishing of lamp 114. 110

As soon as the sequence switch 408 moves out of position 17-3/4 the above-traced circuit is opened and the relays included therein become deenergized. The disconnect lamp 161 and the supervisory lamp 114 light 120 up. When the sequence switch 408 reaches position 18-1/2, a circuit is closed from the negative pole of grounded battery, through the upper winding of relay 404, the lower contact of sequence switch spring 406, conductor 401, and then through relays 153 and 151, and back through conductor 400, the lower contact of sequence switch spring 405, the lower winding of relay 404 and the winding 125 of relay 403 to the positive pole of bat- 130

tery. The relays 404 and 153 become energized, but due to the relatively high resistance of the circuit, the relay 403, and due to the direction of the current, the relay 151 5 remains deenergized. The lamp 161 is extinguished and the relay 404 causes the sequence switch 408 to perform another revolution. By interrupting this circuit at the lower left-hand contact of spring 406, the 10 sequence switch 408 causes through the agency of relay 153, the flashing of lamp 161.

When the sequence switch 408 reaches position 11, the above-traced circuit through the upper contact of sequence switch springs 15 405 and 406 is again closed, whereupon the relay 151 becomes energized and causes the extinguishing of lamp 114.

The above described operation continues until the A and B operators perceive the 20 overflow signals and sever the connection in the already explained manner.

It will be seen that as long as the sender is connected with the overflow trunk, the marginal relay 403 is energized by current 25 flowing through the circuit including the windings of relay 404, or the locking circuit including the winding of relay 422. The relay 422 being energized, the polarized relay 151 cannot become energized, and furthermore, as above stated, a reversal in the direction of the current flowing through the windings of the sender stepping relay 520, is prevented. If in positions 14 to 18 of the sequence switch 408 the sender is connected 35 with the overflow trunk, the relay 422 is supplied with ground through a resistance 440, the upper contact of sequence switch spring 430, and the front contact and armature of relay 403.

40 What is claimed is:

1. In a telephone exchange system, a calling and a called line, a plurality of selectively operable switching devices for interconnecting said lines, a variably adjustable 45 sender, means for operating said sender in accordance with its adjustment to control the successive setting of said switching devices, and other means for controlling the operation of said sender in accordance with 50 its adjustment and irrespective of the setting of said switching devices.

2. In a telephone exchange system, a variably adjustable sender, a plurality of selectively operable switching devices, means 55 for adjusting said sender to perform certain operations for controlling the setting of said switching devices, means controlled by said devices for causing said sender to complete said certain operations, and means 60 separate from said devices for causing said sender to perform said certain operations.

3. In a telephone exchange system, a series of selectively operable switching devices, a sender, means for adjusting said 65 sender to successively control the setting of

said devices, and means operable upon the setting of the first device in the series and independent of the other devices for controlling said sender to complete its operation.

4. In a telephone exchange system, a series of selectively operable switching devices, a sender, means for adjusting said sender in accordance with the desired setting of all of said switching devices, means 75 operative thereupon and successively controlled by said devices for restoring said sender to normal, and means operable upon the setting of the first device of said series for controlling the restoration of said sender 80 independent of the operation of said switching devices.

5. In a telephone exchange system, two lines, means including a series of selector switches for establishing a connection between said lines, a set of counting relays, means successively controlled by each of said selectors in their selecting operation for operating said counting relays in a certain predetermined manner, and automatic means 90 operable upon the initiation of said connection for operating said counting relays in said predetermined manner.

6. In a telephone exchange system, a calling and a called line, a selector switch, 95 means for extending the calling line thereto, a plurality of trunk lines arranged for seizure by said selector switch, another selector switch arranged to extend any one of said trunk lines toward the called line, 100 a sender adjustable to control the setting of said selector switches, means successively operable by said switches during their selecting operations for operating said sender in accordance with its adjustment, and 105 means separate from said second selector switch for operating in conjunction with said first mentioned selector switch said sender in accordance with its adjustment.

7. In a telephone exchange system, two 110 lines, means including selector switches and trunk lines for establishing a connection between said lines, a supervisory signal associated with one of said trunk lines, a polarized relay adjusted for operation in response to current of a certain direction for controlling said supervisory signal, means operable during the establishment of said connection for sending current through said supervisory relay in the opposite direction, means operable through said called line for sending current through said relay in said certain direction, an overflow trunk, and means operable through said overflow trunk for causing the sending of current in a certain 120 direction through said polarized relay.

8. In a telephone exchange system, two lines, means including selector switches and trunk lines for establishing a connection between said lines, a supervisory signal asso- 125

- ciated with one of said trunk lines, a polarized relay adjusted for operation in response to current of a certain direction controlling said supervisory signal, means operable during the establishment of said connection for sending current through said supervisory relay in the opposite direction, means operable through said called line for sending current through said relay in said 5 certain direction, an overflow trunk, and means controllable through said overflow trunk for intermittently changing the direction of current sent through said polarized relay.
- 10 15. 9. In a telephone exchange system, a calling and called line, means including a plurality of selector switches and trunk lines for establishing a connection between said calling and called lines, a variably adjustable sender for controlling the operation of said selector switches, means successively controlled by said selector switches during their setting for causing the restoration of said sender, a supervisory signal, means for 20 25 operating said signal upon the successful establishment of said connection, an overflow trunk, means including one of said selector switches for connecting said sender to said overflow trunk, means controllable through said overflow trunk for causing the restoration of said sender, and other means controllable through said overflow trunk upon the restoration of said sender for operating said supervisory signal.
- 30 35. 10. In a telephone exchange system, a calling and called line, means including selector switches and trunk lines for interconnecting said calling and called lines, a variably adjustable sender for controlling the setting of said selector switches, means successively operable in response to the setting of said selector switches for restoring said sender to normal, a supervisory signal associated with one of said trunk lines, a polarized relay adjusted for operation in response to current of a certain direction controlling said signal, means operative during the establishment of said connection for sending current in the opposite direction through 40 45 50 55 60 65 said relays, means controllable through the called line for sending current in a certain direction through said relay, an overflow trunk, means including one of said selector switches for associating said sender therewith, means operable through said overflow trunk for causing the restoration of said sender, and means operable upon the restoration of said sender and controlled through said overflow trunk for causing the sending of current in a certain direction through said relay.
11. In a telephone exchange system, a calling and called line, means including a plurality of selector switches and trunk lines for establishing a connection between said 65
- calling and called lines, a variably adjustable sender for controlling the operation of said selector switches, means successively controlled by said selector switches during their setting for causing the restoration of 70 said sender, a supervisory signal, means for operating said signal upon the successful establishment of said connection, an overflow trunk, means including one of said selector switches for associating said sender 75 with said overflow trunk, a sequence switch associated with said overflow trunk, means operable upon the association of said sender with said overflow trunk for causing said sequence switch to perform a plurality of 80 revolutions, means operable during one of said revolutions for causing the restoration of said sender, and means operable during another revolution of said sequence switch for operating said signal. 85
12. In a telephone exchange system, a calling and a called line, a plurality of groups of trunk lines, means for rendering said trunk lines busy, a selector switch, means for extending the calling line thereto, a sender, means for adjusting it to determine the setting of said selector switch, means for operating said selector switch to select a group of said trunk lines, means operable during the selective movement of said switch for causing the operation of said sender in accordance with its adjustment, means operable thereupon for causing said switch to select and seize an idle trunk line in the selected group, a second selector switch, means for adjusting said sender to determine the setting of said second selector switch, means for operating said second selector switch to extend the seized trunk line toward the called line, means operable by 90 95 100 105 110 115 120 125 130 said second selector switch during its operation for causing said sender to operate in accordance with its last mentioned adjustment, and means for causing said sender to operate in accordance with its second adjustment if all the trunk lines in said selected group are busy.
13. In a telephone exchange system, a calling and a called line, means including a plurality of selector switches and trunk lines for establishing a connection between said calling and called lines, a variably adjustable sender for controlling the setting of said selector switches, a relay associated with said sender for controlling its restoration, a circuit for said relay, means for extending said circuit successively to said selector switches, an overflow trunk, means including one of said selector switches for extending said circuit to said overflow trunk, means arranged to control the sending of current through said trunk in both directions, and means operable while said circuit is connected to said overflow trunk for preventing the sending of current in a certain direction. 130

14. In a telephone exchange system, a calling and a called line, means including a plurality of selector switches and trunk lines for establishing a connection between said calling and called lines, a variably adjustable sender for controlling the setting of said selector switches, a relay associated with said sender for controlling its restoration, a circuit for said relay, means for extending 5 said circuit successively to said selector switches, a supervisory signal associated with one of said trunk lines, a polarized relay for controlling said supervisory signal, means operable upon the completion of said 10 connection for sending current in the proper direction through said polarized relay, an overflow trunk, means including one of said 15 selector switches for extending the circuit of said relays to said overflow trunk, a switch at said overflow trunk arranged to 20 control the sending of current through said trunk in both directions, means operable while the circuit of said first mentioned relay is connected to said overflow trunk for preventing the sending of current in a cer- 25 tain direction, and means operable upon the restoration of said sender for permitting said switch to send currents of both directions through said circuit to intermittently 30 operate said polarized relay.

In witness whereof, I hereunto subscribe my name this 29th day of June, A. D. 1917.

ALBEN E. LUNDELL.
